UNITED STATES PATENT OFFICE

1,974,749

SEWING MACHINE

Francis J. McAvinney, Dorchester, Mass., assignor
to The Reece Button Hole Machine Company,
Boston, Mass., a corporation of Maine

Application October 8, 1931, Serial No. 567,563

4 Claims. (Cl. 74—104)

This invention relates to sewing machines and particularly to the looper-actuating mechanism of sewing machines of the general type illustrated in United States patents, No. 1,352,280, September 7, 1920, No. 1,558,182, October 20, 1925, and No. 1,743,356, January 14, 1930. In these sewing machines the looper mechanism is carried by a turret which is mounted in the frame beneath the work for rotative movement to provide for sewing around the ends of the buttonhole and the loopers and looper spreaders are given their operative movements by means of concentric spindles situated axially of the turret and capable of reciprocation in the direction of their length, each spindle deriving its reciprocating movement from a vibrating lever.

The connection between each lever and the spindle must be a pivotal connection to allow for swinging movement of the lever and it must also be in the nature of a swivel connection to permit the turning of the spindle with the turret as the latter turns in sewing around the end of the buttonhole. The present invention relates particularly to a novel connection between the spindle which operates the looper and its actuating lever, and has for its object to provide a novel connection which is simple to manufacture, which is effective in allowing the required pivotal and swivel movement between the connected parts and which can be readily adjusted as wear takes place.

In order to give an understanding of the invention I have illustrated in the drawing a selected embodiment thereof which will now be described after which the novel features will be pointed out in the appended claims.

Fig. 1 is a view of the turret of a sewing machine of the general type illustrated in the above-mentioned patents, said figure illustrating my improved connection between the actuating lever and the spindle which actuates the looper spreaders;

Fig. 2 is a sectional view on the line 2—2, Fig. 1;
Fig. 3 is a section on the line 3—3, Fig. 1;

Fig. 4 is a side view of Fig. 1 with a part broken out;

Fig. 5 is a section on the line 5—5, Fig. 1.

In the drawing 1 indicates generally the turret of a buttonhole sewing machine of the general type illustrated in said above-mentioned patents, No. 1,352,280, September 7, 1920, No. 1,558,182, October 20, 1925, and No. 1,743,356, January 14, 1930, it being understood that said turret is mounted for rotative movement in the frame beneath the work and that it carries the

looper mechanism which co-operates with the upper needle in concatenating the stitches.

The looper mechanism comprises vibrating loopers and looper spreaders, which are not illustrated in Fig. 1 of the drawing since said figure shows the opposite side of the turret from that on which the loopers and looper spreaders are actuated. It may be said, however, that the loopers and looper spreaders are carried on a looper carrier 2 pivoted to the turret at 3, said carrier being connected by a link 7 to a collar 8 on a spindle 9 extending axially through the turret and connected at its lower end to an actuating lever 10.

The looper spreaders are actuated by an oscillating cam member 6 which is connected by a link 4 to a spindle 5 also situated axially of the turret 1 and reciprocable vertically therein. As usual in devices of this sort the spindle 9 is in the form of a sleeve and the spindle 5 extends through it axially. The spindle 5 is given its vertical reciprocation in any suitable way. The lower end of the spindle or sleeve 9 is connected to one end of and is actuated by a lever 10 which is suitably pivoted to the frame as shown at 11, said lever deriving its oscillating movement from some appropriate moving part of the sewing machine.

The present invention relates particularly to the connection between the spindle 9 and the lever 10. As stated above, said connection must provide the necessary pivotal connection between the spindle 9 and lever 10 as well as allowing the spindle 9 to turn about its axis relative to the lever 10 as the turret is turned.

The lever 10 is of fixed length and oscillates about a stationary axis 11. It is shown as having a forked end 12 and each arm 13 of the fork 12 is provided with an inwardly-directed stud or trunnion 14. These trunnions 14 are shown as being formed on the inner ends of studs 15 which are mounted in the arms 13, each stud having fast thereon a collar 16 engaging the inner face of the arm and having a nut 17 screw threaded to its outer end for locking the stud in place.

The trunnions 14 are connected to the spindle 5 through the medium of a swivel member which is journalled on the trunnions 14 and is mounted on the spindle 9 for turning movement thereabout and bodily movement transverse to the axis thereof, but which is held from movement longitudinally of said axis. This swivel member is shown as comprising the two swivel rings 18 and 19 which are confined between a collar 20 and

that is rigid with the spindle 9 and a second collar 21 which is adjustably mounted on the spindle. As herein shown the collar 21 is screw threaded to the lower end of the spindle as shown at 22 and said collar is split as indicated at 23, the split portion of the collar carrying a clamping screw 24 by which the collar can be clamped to the spindle.

Each swivel ring 18, 19 is formed on the edge 10 thereof which faces the other ring with notches 25 shaped to fit the trunnions 14, the notches in the two rings being in alignment and each pair of aligned notches thus forming a bearing for the corresponding trunnion.

15 The swivel rings 18, 19 are thus held between the collars 20, 21 but are free to turn about the spindle, or, in other words, the spindle 9 is free to turn within the rings. Moreover, the interior diameter of each swivel ring is somewhat 20 larger than the exterior diameter of the portion 26 of the spindle on which said rings are mounted so the rings may have a movement transversely of the axis of the spindle.

25 The connection between the trunnions 14 and the swivel rings 18, 19 together with the transverse motion which the rings may have provide the necessary pivotal connection between the lever 10 and the sleeve 9 by which the arcuate motion of the trunnions 14 is converted into a straight line motion of the spindle. With this construction the amplitude of the straight line movement of the spindle corresponds exactly to the vertical component of the amplitude of movement of the trunnions 14 but the transverse sliding movement of the swivel rings between the collars 20 and 21 compensates for the difference in the paths of movement between the trunnions 14 and the spindle. The swivel connection between the rings 18 and 19 and the spindle 9 provides for the necessary free turning movement of 40 the turret.

35 The adjustable collar 21 provides means for taking up any wear which may occur between the trunnions 14 and the swivel rings 18, 19 and by this construction it is possible to maintain a tight joint free from loose motion or back lash.

40 The connection is easily assembled and can be easily adjusted to take up any wear without in any way dismantling the sewing machine.

45 I claim:

1. In a device of the class described, the combination with a rotatable spindle reciprocable in the direction of its length, of a forked actuating 50 lever for reciprocating the spindle, said lever having a trunnion projecting from each arm of its fork, two swivel rings carried by the spindle and adapted to turn thereon but held from movement longitudinally thereof, said rings having

55

aligned notches constituting bearings for the trunnions.

2. In a device of the class described, the combination with a rotatable spindle capable of reciprocating in the direction of its length, said spindle having two collars thereon, one of which is fixed and the other of which is adjustable longitudinally of the spindle, a pair of swivel rings confined between said collars but capable of turning about the spindle, said rings having aligned notches, and an actuating lever having trunnions finding a bearing in said notches. 80

3. In a device of the class described, the combination with a spindle rotatable about a fixed axis and capable of reciprocation in an axial direction, of an actuating lever of fixed length oscillating about a stationary axis, and means connecting the ends of said lever with said spindle, said means comprising a two-part annular member through which the spindle extends, trunnion members on the lever situated between and having a pivotal engagement with the two parts of said annular member, said trunnions and the two parts of the annular member having complementary cylindrical bearing surfaces, which fit and turn on each other, whereby a relative movement between said member and lever is confined to a relative turning movement about the axis of the cylindrical bearing surfaces, said spindle having two collars adjustable relative to each other between which the two-part annular member is retained and by the adjustment of which a tight fit between the complementary cylindrical bearing surfaces may be maintained. 90

4. In a device of the class described, the combination with a rotary spindle capable of reciprocating in the direction of its axis and having two collars thereon, adjustable axially relative to each other, of two swivel rings confined between said collars and through which the spindle extends 110 and in which it is free to rotate, said swivel rings being capable of movement relative to the spindle in a direction transverse to the spindle axis, an actuating lever of fixed length oscillating about a stationary axis and having trunnion portions received between said swivel rings, said rings and trunnion portions having complementary cylindrical bearing surfaces that permit a relative turning movement only between said lever and said rings whereby as the lever oscillates said rings move in an arc having said stationary axis as a center, and thereby cause reciprocation of the spindle, and during such arcuate movement said rings also move relative to the spindle in a direction transversely to the axis thereof, the adjustment of the collars providing for maintaining a tight fit between the complementary cylindrical bearing surfaces. 115
